(57) **CLAIM**

The ornamental design for a ultrasonic/electromagnetic pest repeller with digital clock, as shown and described.

DESCRIPTION

FIG. 1 is a perspective view of a ultrasonic/electromagnetic pest repeller with digital clock, showing our new design; FIG. 2 is a front view of the ultrasonic/electromagnetic pest repeller with digital clock shown in FIG. 1; FIG. 3 is a left side view of the ultrasonic/electromagnetic pest repeller with digital clock shown in FIG. 1; FIG. 4 is a rear view of the ultrasonic/electromagnetic pest repeller with digital clock shown in FIG. 1; FIG. 5 is a right side view of the ultrasonic/electromagnetic pest repeller with digital clock shown in FIG. 1; FIG. 6 is a top view of the ultrasonic/electromagnetic pest repeller with digital clock shown in FIG. 1; and, FIG. 7 is a bottom view of the ultrasonic/electromagnetic pest repeller with digital clock shown in FIG. 1. The broken line showing of environment in the drawings is for illustrative purposes only and forms no part of the claimed design.
